UNITED STATES PATENT OFFICE.

HENRY CROSSMAN, OF TOLEDO, OHIO.

POCKETBOOK HOLDER.

Application filed July 23, 1925. Serial No. 45,475.

To all whom it may concern:

Be it known that I, HENRY CROSSMAN, a citizen of the United States, and a resident of Toledo, in the county of Lucas and the 5 State of Ohio, have invented a new and useful Pocketbook Holder, which invention is fully set forth in the following specification.

My invention has for its object to provide 10 a combined pocketbook and key holder which is so constructed that the pocketbook may be readily connected to the holder and the holder may be readily secured to the pocket. The construction is such that the 15 pocketbook may be slipped into position on the holder and the holder slipped over the edge of the pocket and then locked to the pocket. In the preferred form of construction the locking means also provides for securing a key ring to the holder.

The invention may be contained in structures for readily securing various articles in position with reference to garments worn by the user of the invention. To illustrate a 25 practical application of the invention, I have shown clips to which a pocket book and keys may be readily connected and secured in position in the pocket of a garment such as a coat of a wearer, and shall describe them 30 hereinafter. The clips selected as an example are shown in the accompanying drawings.

Figure 1 illustrates a side view of a clip selected as an example of structures embodying my invention and shown as being 35 secured in the pocket of the coat. Fig. 2 illustrates a view of a section through the clip, an end view being shown of a pocketbook that is secured to the clip. Fig. 3 40 illustrates a portion of the pocketbook to illustrate rings that are secured to the pocketbook and which are connected when desired to the clip shown in Figs. 1 to 3. Fig. 4 illustrates a front view of a modified 45 form of clip. Fig. 5 illustrates a section taken on the plane of the line 5—5 indicated in Fig. 4.

The clip shown in Figs. 1 to 3 consists of a sheet metal elastic strip 1 that is bent at 50 its central portion as at 2. One end 3 is turned outward to form a lip whereby the strip 1 may be readily slipped into a pocket 22, the lip 3 being located on the outside of the pocket. On one leg of the strip 1 is located a strip 4 that is secured at one end to

the leg 6 of the strip 1 by means of the rivet 7. The strip 1 has a part 5 and the strip 4 is so bent that the major portions of the strip 4 and the part 5 are located in spaced and parallel relation to the leg 6. The strip 4 and the part 5 extend towards each other and their free ends overlap as shown at 8. The end of the strip 4 being located on the inside of, that is, between the upper end of the part 5 and the leg 6 of the strip 1. 60 Also the strip 4 is so bent that it elastically makes contact with the end of the strip 1 where they overlap. A pocketbook 9 may be provided with one or more rings, such as, the rings 10, and may be connected to the strip 1 by slipping the rings between the overlapping ends of the strips 4 and 1. If the pocketbook 9 is provided with more than one ring 10 the rings 10 are preferably spaced apart so that when they are placed 70 in position on the strips 4 and 1 the upper ring 10 will be located well above the overlapping ends of the strips 4 and 1. When the pocketbook 9 is provided with two rings 10, the rings may be inserted in position on the strips 4 and 1, by slightly folding the pocketbook along the line between the rings 10. 75

The strip 1 is secured to the pocket by means of a pivoted member 11 that is connected to the leg 12 of the strip 1. The leg 12 of the strip 1 is provided with a pair of ears 13 that are bent up from the strip 1 and the pivoted member 11 is provided with outwardly extending lugs 14 that pass through the ears 13 and so as to pivotally move between the lugs 14. The member 11 has a part 15 that overhangs the lip 3 and so that it may be moved towards the leg 6 of the strip 1 and make contact with the leg 6. The end of the overhanging part 15 may be provided with a serrated edge for engaging the cloth of a part of the garment, if the garment is located between the end 15 and the leg 6 of the strip 1. The member 11 is resiliently held from contact with the leg 6 of the strip 1 by means of a spring 16 that is secured to the leg 12 of the strip 1 and is bellied outward at a point below the lugs 14 that pivotally connect the member 11 to the ears 13 and so as to push the lower end 15 of the strip 11 outward from the strip 1. This outward movement, however, is limited by means of a latch member 17 that is pivotally connected to the ears 13 by 85 90 95 100 105 110

lugs 18 that extend outward through the ears 13. The latch member 17 has an end portion 19 that is located substantially at right angles to the body portion of the latch 17 and so that when the latch 17 is turned down it will press against the member 11 which will force the end 15 of the member 11 towards the leg 6 of the strip 1 against the yielding resistance of the spring 16. Preferably the construction is such that the end 15 of the pivoted member 11 will be forced against the leg 6 of the strip 1. When, however, it is desired to release the clip from the garment, the latch 17 may be raised and by reason of the elasticity of the spring 16 the bellied portion will push the member 11 outward so that the serrated edge of the end 15 will be located remote from the leg 6 of the strip 1 and so that the turned end 3 of the leg 12 of the strip 1 will act as a guide for the insertion of the clip into position relative to a part of the garment, such as, into the side of a pocket.

If desired the latch 17 may be provided with a returned portion 20 and so as to form an elastic hook and a key ring 21 may be secured to the hook. Thus the clip may be used for not only securing a pocketbook in position in a pocket but also for securing a ring of keys to a part of the garment of the user of the invention.

In the form of clip shown in Figs. 4 and 5, a spring 25 is secured to the leg 12 of the strip 1 and the latch 17 operates through an opening 26 formed in the leg 12 to press the spring towards the leg 6 of the strip. The spring has a turned end 28 that will be pressed against the leg 6 of the strip to secure the clip to a part of the garment. A spring hook member 29 may be pivotally

secured to the strip 1 for securing any object, such as, a pocketbook, to the clip.

I claim:

1. In an elastic clip, a bent strip having leg portions, an elastic strip secured to one leg portion of the said bent strip for elastically and removably connecting an object to the clip, a spring operated member, a latch member pivotally supported on one leg of the said bent strip and having an end portion turned at right angles to the body portion of the latch and in position to engage the said spring operated member and so as to press the end of the said spring operated member towards the other leg of the strip against the yielding resistance of the spring.

2. In an elastic clip, a bent strip having leg portions, a pair of elastic strips secured to one leg portion of the said bent strip and having overlapping ends that are elastically maintained in contact with each other, an object having a ring and secured to the bent strip by insertion of the ring between the overlapping strips, a pivoted member secured to the other leg of the bent strip, a spring having a bellied portion for maintaining one end of the pivoted member remote from the first named leg, a latch member pivotally supported on one leg of the said bent strip and having an end portion turned at right angles to the body portion of the latch and in position to engage the said pivoted member so as to press the end of the said pivoted member towards the first named leg of the strip against the yielding resistance of the said spring.

In testimony whereof I have hereunto signed my name to this specification.

HENRY CROSSMAN.
